(57) **CLAIM**

We claim the ornamental design for a panel bracket, as shown and described.

DESCRIPTION

FIG. 1 is a left perspective view of a panel bracket of the new design;

FIG. 2 is a right perspective view of the panel bracket of FIG. 1;

FIG. 3 is a top side view of the panel bracket of FIG. 1;

FIG. 4 is a side view of the panel bracket of FIG. 1, the opposite side being a mirror image thereof;

FIG. 5 is a bottom side view of the panel bracket of FIG. 1;

FIG. 6 is a front view of the panel bracket of FIG. 1;

FIG. 7 is a left perspective view of a second embodiment of the new design.

FIG. 8 is a right perspective view of the panel bracket of FIG. 7;

FIG. 9 is a top side view of the panel bracket of FIG. 7;

FIG. 10 is a side view of the panel bracket of FIG. 7, the opposite side being a mirror image thereof;

FIG. 11 is a bottom side view of the panel bracket of FIG. 7; and,

FIG. 12 is a front view of the panel bracket of FIG. 7.

The broken lines are shown for illustrative purposes only and form no part of the claimed design.
